CLAIM

The ornamental design for a cleaning head assembly for a vacuum cleaner, as shown and described.

DESCRIPTION

FIG. 1 is a front, right perspective view of a cleaning head assembly for a vacuum cleaner showing our new design;
FIG. 2 is a front view thereof;
FIG. 3 is a rear view thereof;
FIG. 4 is a left view thereof;
FIG. 5 is a right view thereof;
FIG. 6 is a top view thereof; and,
FIG. 7 is a bottom view thereof.

The broken lines shown on the drawings depict portions of the cleaning head assembly for a vacuum cleaner that form no part of the claimed design.

1 Claim, 5 Drawing Sheets
